W. J. KAMMERER

SEPARABLE FASTENER

Filed March 10, 1924

INVENTOR.

BY Geo. B. Beeler ATTORNEY

UNITED STATES PATENT OFFICE.

WILLIAM J. KAMMERER, OF NEW YORK, N. Y.

SEPARABLE FASTENER.

Application filed March 10, 1924. Serial No. 698,169.

To all whom it may concern:

Be it known that I, WILLIAM J. KAMMERER, a citizen of the United States, residing at New York city, borough of Manhattan, in the county of New York and State of New York, have invented certain new and useful Improvements in Separable Fasteners, of which the following is a specification.

This invention relates to separable fasteners comprising engaging stud and socket members, and has particular reference to such devices as are used on automobile curtains, draperies, suit cases, brief bags, and for similar purposes.

15 My invention provides a fastener which while designed primarily to secure a curtain or other fabric to a rigid member, may be readily altered as to various details so as to include a very wide variety of uses where 20 a fastener at once reliable and easily detachable may be desired. Another object of my invention is to provide a fastener consisting of stud and socket members so that either the one or the other may with only slight 25 changes in construction be fastened to the curtain or to the rigid member as may be desired. Another object of my invention is to provide a fastener that possesses evident and marked advantages over prior devices as 30 to the cost of manufacture and assemblage.

With the foregoing and other objects in view the invention consists in the arrangement and combination of parts hereinafter described and claimed, and while the invention 35 is not restricted to the exact details of construction disclosed or suggested herein, still for the purpose of illustrating a practical embodiment thereof reference is had to the accompanying drawings, in which like 40 reference characters designate the same parts in the several views, and in which—

45 Figure 1 is a central longitudinal section showing the construction of the fastener and the method of attachment when the stud is attached to the curtain.

Fig. 2 is a sectional view taken along the line 2—2 of Fig. 1.

50 Fig. 3 is a central longitudinal section of the fastener showing its construction and the method of attachment when the socket member is attached to the curtain.

Fig. 4 is a sectional view taken along the line 4—4 of Fig. 3.

55 Fig. 5 is an enlarged sectional view of a detail of Fig. 3.

Referring now more specifically to the

drawings, and first to Figures 1 and 2 to disclose one modification of the fastener, I show a separable fastener comprising essentially a head 1 mounted upon a shank 2 and a split socket member 3 slidably located within the casing 4 so as to be locked over the head 1 by the contraction of the resilient ring 5 against the two parts of the split member.

60 As indicated the head 1 comprises entrance securing means in the form of a cone, and an upper portion 27 likewise of conical form for ready disengagement of the fastener. The last mentioned conical portion has sides inclined at a greater angle to each other than the entrance securing cone in order that it may be easier to insert the head into the socket than to withdraw it. The junction of the two cones is rounded along 75 the periphery as shown at 6 in order to minimize whatever little wear the head may under the worst conditions suffer.

70 The socket member 3 is in the form of a circular ring centrally divided into halves along the vertical axis and of cylindrical channel section. The upper and lower flanges 28 of the socket provide means to enable the two portions or sections of said socket to slide readily within the casing 4, and are sufficiently wide to prevent tilting of said portions which the forces applied at the upper or lower ends of the socket by the head would have a tendency to cause 80 when attempting to attach or separate the fastener. The socket member is also beveled off along its inner edges as shown at 7 and 8 substantially parallel with the elements of that conical portion of the head 1 with which such beveled edge is to engage. This 85 construction in co-operation with the rounded edge 6 of the head effects a more easy operation of the fastener by reducing to a minimum all unnecessary friction. Being 90 thus independent of friction, a scientific design of the fastener is possible in that the sizes of the angles of the conical portions of the head 1 may now be proportioned directly as the magnitude and the ratio of the forces desired to operate the fastener.

95 The cylindrical casing 4 has in one of the bases a central cylindrical recess or extension 9 having a hole adapted to receive a screw 10. The rim portion of said hole is constructed with a bead 11, for reinforcing 100 and stiffening the extension 9 at the point of attachment of the screw. The extension

is likewise of sufficient size to receive the entire head 1. In the opposite base of the casing 4, there is an opening 13 of relatively considerable size, yet leaving sufficient metal on that base for the socket to engage with and slide upon.

The resilient ring 5 is made preferably of rubber and is adapted at 14 to embrace the body of the socket member 3. At both sides 10 it has circular rabbets, as at 15, to receive the flanges of the socket member, the ring itself being of sufficient size to substantially fill the casing 4 when under stress, thus preventing any possible tilting or side-springing of the ring.

The rigid support 12 is of course to be recessed so as to receive the casing 4, the face of the casing being preferably flush with the side of the supporting member.

20 Secured to the shank 2 is the finger piece 16 fastened to a circular plate 17 which cooperates with a circular plate 18 having prongs 19 adapted to lock over the plate 17 so as to hold the curtain 20 in rigid attachment therebetween. This double plate construction has the advantage of eliminating the possibility of ripping the curtain if the curtain should suffer a severe lateral pull.

The fastener illustrated in Figures 3 and 30 4 embodies all the unique principles of construction of the fastener shown above, and indicates another preferred construction of the invention. It is worthy of note that the two fasteners differ very little from each 35 other as to details of construction and operation, and that therefore both designs may at once be used readily for practical purposes.

As shown the head member is attached 40 to the rigid support 12, while the socket portion is borne by the curtain 20. The head 1 and the shank 2 are identical with those shown in Figs. 1 and 2 except that the shank terminates in a screw 10'. The 45 screw 10' is notched out at 21 to receive the extension or lug 22 of the plate 23 so as to prevent any relative rotation as between said plate and said screw. Therefore by adding the nail 24 to prevent the plate 23 from rotating, all chances of the screw coming loose are eliminated.

50 As mounted upon the curtain, the recess 9' of the casing 4' now forms the finger piece, and so in order to facilitate the grasping thereof, it is fitted with a peripheral end portion 9''. The casing 4' has a flange 29 adjacent to the curtain 20, and prongs 17' which after being passed through the curtain are adapted to lock or clinch over the 55 plate 25. The peripheral portion of the plate 25 is offset so that the face of the prongs 17' when they are locked in place

will coincide with the face of the plate 25. This plate has an opening 26 for allowing the passage of the head 1 therethrough. The resilient ring 5 substantially fills said casing about the socket member 3.

I claim:

1. A fastener comprising a headed shank, a casing to receive said shank, a socket member within the casing and consisting of a plurality of hollow partially cylindrical portions having parallel curved end flanges surrounding the same, the shank head being projectable through the socket member, and resilient means co-operating with the socket member tending to cause the portions thereof to approach one another to form a hollow cylinder and thereby embrace the shank and interlock with said head, said casing having flat faces against which said flanges are slidably when actuated by said resilient means.

2. A fastener comprising a casing, a head, a socket member extending across the casing and adapted to receive said head and to slide in the casing and having flanges located at the ends of the socket member, and a resilient rubber member extending across the casing and recessed to receive said flanges, said socket member consisting of a plurality of symmetrical portions actuated toward each other by said resilient member so as to lock behind said head.

3. In a separable fastener, the combination of a shank having a head, a cylindrical casing, a solid rubber ring within and confined by said casing, and a socket member composed of a plurality of relatively movable parts constituting a sleeve lining said ring and extending from one flat side of the casing to the other and through which said head is adapted to be forced, the resiliency of the rubber acting to cause the parts of the sleeve to move toward the axis of the ring and casing to retain the parts together.

4. In a separable fastener, the combination with a shank having a head, a casing having an opening spaced from the sides thereof to permit the entry of said head, and a socket member within said casing composed of a plurality of relatively movable parts adapted to receive and to lock behind said head, of a rubber ring contacting the sides of said casing and adapted to contain said socket member so as to actuate the parts thereof toward each other, said ring serving to hold said socket member in alinement with said opening for the ready reception of said head.

In testimony whereof I affix my signature.

WILLIAM J. KAMMERER.
